CLAIM

The ornamental design for an automobile lower bumper, as shown and described.

DESCRIPTION

FIG. 1 is a front perspective view of an automobile lower bumper attached to a vehicle, no part of the vehicle is claimed;

FIG. 2 is a perspective view of the automobile lower bumper;

FIG. 3 is a front elevational view of the automobile lower bumper;

FIG. 4 is a top plan view of the automobile lower bumper; FIG. 5 is a left side elevational view of the automobile lower bumper (the right side view is a mirror of the left side view and is not shown); and,

FIG. 6 is bottom plan view of the automobile lower bumper. The broken lines are for illustrative purposes only and form no part of the claimed design.

1 Claim, 6 Drawing Sheets
